UNITED STATES PATENT OFFICE.

GEORGE B. FRANCIS AND BRONSON H. SMITH, OF NEW YORK, N. Y., ASSIGNORS TO WESTINGHOUSE, CHURCH, KERR & COMPANY, OF NEW YORK, N. Y., A CORPORATION OF NEW JERSEY.

DESIGN FOR A MOTOR-TRUCK BODY.

45,105.

Specification for Design.

Patented Jan. 6, 1914.

Application filed August 8, 1911. Serial No. 643,065. Term of patent 7 years.

To all whom it may concern:

Be it known that we, GEORGE B. FRANCIS and BRONSON H. SMITH, citizens of the United States, residing, respectively, at New York city, county of New York, and State of New York, and New York city, county of Kings, and State of New York, have invented a new, original, and ornamental Design for a Motor-Truck Body, of which the following is a specification, reference being had to the accompanying drawings, forming part thereof.

Figure 1 is a perspective view and Fig. 2 is a view in side elevation of a motor truck body showing our new design.

We claim:

The ornamental design for a motor truck body, as shown.

GEORGE B. FRANCIS.
BRONSON H. SMITH.
